ADJUSTABLE FLOODGATE

Cyril J. Droessler, Jamestown, Wis.

Application May 27, 1949, Serial No. 95,735

1 Claim. (Cl. 39—4)

1

This invention relates to flood gates such as are employed across streams.

The principal object of this present invention is to provide a durable flood gate, having depending swingable members capable of yielding when floating debris strikes the same and then returning to their normal vertical positions.

Another important object of the invention is to provide a flood gate of the above character, which is capable of being easily installed, much more so than present day gates.

A further object of the invention is to provide a flood gate which can be readily adjusted to meet the unevenness of the stream bottom.

These and various other objects and advantages of the invention will become apparent to the reader of the following description.

In the drawing:

Figure 1 is a side elevational view of the gate, this also being a section taken transversely 20 through the stream and its banks.

Figure 2 is a fragmentary perspective view showing part of the supporting chain and one of the depending gate units.

Figure 3 is a fragmentary enlarged view of 25 the gate unit shown in Figure 2 with parts in vertical sections.

Figure 4 is a cross section taken on line 4—4 of Figure 3.

Referring to the drawing it can be seen that numerals 5, 6 denote a pair of posts having their lower ends set in the banks of a stream as illustrated. These posts may be of wood, concrete or any other desirable material and these are preferably provided at their upper ends with eyes 7, 8 respectively.

Numerical 9 denotes an elongated supporting chain which is connected at its ends to the eyes 7, 8 and clevises may be employed at one or both ends of the chain to permit adjustment thereof with respect to the eyes 7, 8.

Depending from the supporting chain 9 are gate units generally referred to by numeral 10. These units are shown in detail in Figures 2, 3 and 4.

Each unit consists of a pair of vertical rods 11, 12, the upper end of the rod 12 being provided with a loop 13 for embracing the rod 11, while the lower end of the rod 11 is provided with a loop 14 for embracing the rod 12.

The lower end of the rod 12 is free, while adjacent its upper portion, an opening is formed to receive a pin 15 which also projects laterally and through one of the openings 16 in the lower portion of the rod 11, and in this manner the rods are not only interconnected together but positively secured in adjusted position, this to the extent that the lower end of the rod 12 will be the proper distance from the bed or bottom of the stream.

2

It is probable that the upper end of the rod 11 be threaded as at 17 and extend upwardly through one of the horizontal links of the chain 9. A nut 18 is provided on the upper end of the threaded portion 17 and this rests upon the horizontal links to prevent downward displacement of the unit 10.

It can now be seen through the medium of the nut 18 and thread 17 or through the medium 10 of the pin 15 and opening 16, the rods 11, 12 can be adjusted vertically with respect to the bottom of the stream so that they will be in proper relation thereto. As many of these units as is desired may be added and suspended from the chain 9.

Obviously when debris floating down the stream strikes this group of units 10, they will swing and permit the debris to pass thereunder, then returning to their normal vertical position.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

A flood gate comprising a pair of vertical anchor posts, a chain interconnecting the tops of said posts, and a plurality of depending guard elements connected in spaced relation to said chain, each of said elements comprising a vertically extending upper rod having a threaded upper end adapted to extend through said chain, a nut engaged with said threaded end to prevent downward movement of said upper rod, a laterally extending loop at the lower end of said upper rod, a vertical lower rod extending through the loop of said upper rod and having a laterally extending loop at its upper end for receiving therethrough said upper rod, said upper rod having a plurality of spaced transverse openings in its lower portion and said lower rod having a transverse opening adjacent its upper end, and a pin extending through the opening in the lower rod and selectively through one of the openings in the upper rod, whereby the effective length of said element may be controlled.
